UNITED STATES PATENT OFFICE.

RICHARD M. THOMAS, OF GREENSBURG, INDIANA.

DESIGN FOR A SURGICAL STAND.

SPECIFICATION forming part of Design No. 28,436, dated March 29, 1898.

Application filed January 4, 1898. Serial No. 665,587. Term of patent 14 years.

To all whom it may concern:

Be it known that I, RICHARD M. THOMAS, a citizen of the United States, residing at Greensburg, in the county of Decatur and State of Indiana, have invented a new and original Design for a Surgical Stand, of which the following is a specification.

The leading feature of my design for a surgical stand consists of a step-shaped frame 5 and a series of horizontal tables on the steps of such frame.

In the accompanying drawings, Figure 1 is a perspective view of a surgical stand, showing my design. Fig. 2 is a vertical central 15 sectional view thereof.

As shown by the accompanying drawings, my design for a surgical stand consists of a step-shaped frame 5 and a series of tables occupying different horizontal and vertical 20 planes. This frame 1 has short standards 6, long standards 7, and intermediate standards 8, all parallel to each other. The lower parts of the standards are joined by the horizontal rails 9, lying at right angles to the standards.

10 are horizontal rails between the short standards 6 and the intermediate standards 8, and 11 12 are horizontal rails between the long and intermediate standards 7 8. The rails 11 12 are in the same vertical plane at 25 one side of the vertical plane of the rails 10, and these rails 10, 11, and 12 are in different horizontal planes.

13 are other horizontal rails, situated in a

different vertical and horizontal plane from either of the before-mentioned rails 10, 11, and 35 12, and 13^a are inclined braces between the long standards 7 and the terminals of the rails 13.

The standards of varying lengths and the rails 10, 12, and 13 produce a frame which is 40 substantially step-shaped, as shown by the drawings.

On the lower horizontal rails 9, between the standards 6 8, is a horizontal table 14. Another horizontal table 15 occupies the rails 45 10 between the short and intermediate standards 6 8, and this table 15 is parallel to and a considerable distance above the table 14. Other tables 16 17 occupy the rails 11 12, and said tables 16 17 are in the same vertical 50 plane but at one side of the vertical plane of the tables 14 15. The whole series of tables 14 15 16 17 occupy different horizontal planes, the table 16 lying above the table 15 and table 17 lying above table 16. 55

The table 15 has a circular opening 18.

What I claim is—

The design for a surgical stand herein shown and described.

In testimony that I claim the foregoing as 60 my own I have hereto affixed my signature in the presence of two witnesses.

RICHARD M. THOMAS.
